RAZOR HANDLE

Charles Castelli, Philadelphia, Pa., assignor to Johnson & Johnson, New Brunswick, N.J.

Filed Nov. 3, 1971, Ser. No. 195,543

Term of patent 14 years

Int. Cl. D28—03

U.S. Cl. D95—3 A

FIG. 1 is a side elevational view of a razor handle, showing my new design, the appearance being the same from all sides;

FIG. 2 is a cross-sectional view, partly in top plan, taken along line 2—2 in FIG. 1; and

FIG. 3 is a cross-sectional view, partly in top plan, taken along line 3—3 in FIG. 1.

I claim:

The ornamental design for a razor handle, as shown and described.
